UNITED STATES PATENT OFFICE.

JAMES ROWE, OF CHICAGO, ILLINOIS.

PRINTING-PRESS.

SPECIFICATION forming part of Letters Patent No. 753,164, dated February 23, 1904.

Application filed August 7, 1903. Serial No. 168,655. (No model.)

To all whom it may concern:

Be it known that I, JAMES ROWE, a citizen of the United States, residing at Chicago, in the county of Cook and State of Illinois, have 5 invented certain new and useful Improvements in Printing-Presses; and I do hereby declare the following to be a full, clear, and exact description of the invention, such as will enable others skilled in the art to which it appertains 10 to make and use the same.

My invention relates to a novel construction in a printing-press, and has for its object to provide a press through which a continuous web is passed which may be printed on one or 15 both sides and in one or more colors in one operation; and it consists in the features of construction and combinations of parts hereinafter fully described and claimed.

In the accompanying drawings, illustrating 20 my invention, Figure 1 is a side elevation, partly broken away, of a printing-press constructed in accordance with my invention. Fig. 2 is a transverse section of same on the line 2 2 of Fig. 1. Fig. 3 is a fragmentary 25 detail longitudinal section on the line 3 3 of Fig. 2. Fig. 4 is a fragmentary detail view in elevation, showing a bearing of the inking-rollers. Figs. 5 and 6 are detail views in elevation of two forms of clutch mechanism controlling the web-shifting devices. Fig. 7 is a 30 fragmentary detail elevation of the rack and the crank controlling same. Fig. 8 is a transverse section on the line 8 8 of Fig. 7. Fig. 9 is an outline elevation of my press, showing 35 the manner of passing the web in order to print same on one side only. Fig. 10 is a fragmentary detail elevation showing one of the printing-cylinders provided with scoring-knives for cutting paper boxes. Fig. 11 is a 40 detail section on the line 11 11 of Fig. 10.

One of the objects of my invention is to provide a press which is particularly adapted for printing sale-checks, time-tables, and similar matter in very large quantities at minimum 45 cost, this being accomplished by printing one or both sides in one or more colors at a single operation.

Other objects of my invention will appear from the following description.

50 My press comprises a suitable frame 1, on

which are mounted two printing-beds 2 and 3, which consist of two diametrically opposite segments of a cylinder and on the edges of which are concentric racks 4, with which the gears 5 of printing-cylinders 6, 7, 8, and 9 55 mesh. The said printing-cylinders 6, 7, 8, and 9 are revolvably mounted in movable journals 10 in the free ends of arms 11 of an oscillating frame 12, journaled on trunnions 13, concentric with said printing-beds 2 and 3. The 60 said oscillating frame 12 is connected at one end by means of pitmen 14 with the crank-pins of spur-gears 15, meshing with gear-pins 16 on the drive-shaft 17. At a diametrically opposite point said frame 12 is connected 65 with the piston-rods of air-cylinders 18, which serve to steady the movements of said frame and cushion same as it reaches the limits of its movements. Said air-cylinders are mounted 70 on trunnions and oscillate in accordance with the movements of said frame 12. The said cylinders 6, 7, 8, and 9 are designed to receive 75 printing-plates 19, extending only over one-half or less of their circumference, the remaining surface of said cylinders forming an ink-distributing surface which is fed by one of the inking-rollers 20, and from which the remaining rollers 21 are fed. The said inking-rollers 20 and 21 are mounted in movable 80 journal-boxes 22, mounted in guides in the journals 10, and normally held at the inner limits of their movement by means of springs 23. The said journal-boxes 22 each comprise two members hinged together and held in proper relative position by means of set-screws 85 24, said boxes being readily operated to remove the inking-rollers to clean the latter. The inking-surface of each of the printing-cylinders is of less radius than the printing-surface of the plate 19. In order to feed ink 90 to the said inking-rollers 20, I provide further ink-distributing rollers on the frame of the machine, the latter being of common construction and operation, and from the latter are fed two rollers 25, journaled in the free ends of 95 oscillating arms 26, which are operated in accordance with the movements of the frame 12 to throw said rollers 25 into the path of rollers 27, carried and which are movable in U-shaped arms 28 on the journals 10 of the 100

cylinders 7 and 8, said rollers 27 lying normally in contact with the roller 20 and being raised out of contact with the latter when engaged by the roller 25 to receive ink from the latter. Similarly-mounted rollers 27 on the cylinders 6 and 9 are brought into contact with inking-rollers 29 on the frame which lie always in the path of said rollers 27. The said printing-cylinders 6, 7, 8, and 9 are so arranged relatively to the printing-beds as to print only during a part of the movement of the frame—that is to say, that during the first and last quarters of the movement of said frame 12 said cylinders do not print by reason of the fact that during said movements the inking-surfaces of said cylinder are presented toward the beds and by reason of their smaller radius are not brought in contact with the web, two of said cylinders having passed beyond the ends of said beds, but are brought into printing position during the second and third quarters of the stroke of said frame 12. During such first and last quarters of the stroke of said frame 12 the continuous web 30 of paper is shifted to bring a fresh portion of its surface into position, while during the second and third quarters of the stroke said web remains stationary. This I accomplish in the following manner: The web 30 is taken from a roll 31, revolvably mounted in suitable bearings at one end of the machine, and is trained over idlers 32, 33, and 34 and then passes over the bed 2. Upon leaving said bed it passes over a roller 35, which is intermittently rotated, as hereinafter described, and is then trained over a pair of compensating rollers 36, suitably journaled in an oscillating frame 37, which may be adjusted to any desired position and then passes over the bed 3, where the opposite side of the web is presented to the printing-cylinders. After passing over said bed 3 said web is trained over a second intermittently-rotated roller 38, then over a second compensator 39, thence over a third intermittently-rotated roller 40, which feeds it to cutting devices 41, where said web is cut into sheets of uniform length. The said intermittently-rotated rollers 35, 38, and 40 each carry ratchet-wheels or other suitable clutch devices 42, which are rigid with said roller, while on the shaft of the roller is a loosely-mounted rotating gear 43, which carries a clutch dog or dogs 44, which engage said clutch member when said gear rotates in one direction, while when said gear rotates in the opposite direction it revolves freely. Each of said gears 43 of the rollers 35 and 38 is geared to a reciprocating rack 45, while the gears of the roller 40 mesh with a reciprocating rack-bar 46. The said reciprocating rack-bar 45 is enlarged between its ends and is provided with a vertical slot 47 in said enlarged portion, in which a sliding crank-pin box 48 is movable, which receives the pin 49 of a crank 50, carried by the

shaft 51 of the gear-wheel 52, the latter being one-half the diameter of and meshing with said spur-gears 15. Thus said rack-bar 45 is reciprocated twice for each revolution of said spur-gear 15. During the movement of said rack 45 toward the roll 31 the said gears 43 revolve freely, while upon the reverse movement of said rack they engage the clutch members 42 and rotate said rollers, thereby feeding the web 30 a predetermined distance. The distance which said web 30 is fed must be variable in order to print sheets of various lengths, and to this end the crank-pin 49 is rendered adjustable toward and away from the shaft 51, said pin being slidably mounted in a slot in the crank 50 and having a screw-shaft 53, passing through its inner end, said screw-shaft being rotatably mounted in said crank 50 and held against longitudinal movement therein. The rack-bar 46 is similarly reciprocated by means of a similarly-adjustable crank-pin of the crank 54 of a counter-shaft 55, geared to the spur-gears 15 and revolving at four times the speed of the latter, as hereinafter set forth. As the roll 31 is very heavy, it would be difficult to intermittently revolve the same, particularly as its speed necessarily increases as the web is unwound in order to feed the same length in a given interval. Any attempt at intermittent movement would necessarily involve varying tension on the web, which aside from the danger of tearing might seriously interfere with the register, and consequently I provide means for continuously revolving said roll at a uniform surface speed, so that it will feed the requisite slack between the printing intervals to be taken up by the shifting devices. This I accomplish by means of a belt 56, trained over a driven pulley 57 and over an idler 58, journaled in the free end of a frame 59, pivoted on the shaft of said driven pulley 57, said belt being adapted to rest upon the roll 31 and rotate the same by frictional contact therewith. The shaft of the pulley 57 carries a worm-wheel 60, meshing with a worm 61 on a shaft 62, which at its other end carries a longitudinally-movable friction-gear 63, which is driven from a friction-disk 64, geared to said shaft 51, said gear 63 being movable toward and away from the center of said disk 64 by means of the bell-crank lever 65 in order to vary the speed of said shaft to accord with the variations in stroke of the rack 45.

The feeding of the web from the roll may be accomplished in various ways, and I therefore do not confine myself to the foregoing devices.

In operation my press is as follows: In the position of the oscillating frame 12 shown in Fig. 1 the printing-rollers 6, 7, 8, and 9 are out of printing position and are at one limit of their movement, the web being now free to shift and in motion. The movement of the web continues until the spur-gears 15 have

completed an eighth of a revolution and then remains stationary by reason of the fact that said rack-bar 45 now begins its movement toward the roll 31. As soon as said spur-gears 15 have completed said one-eighth of their revolution the cylinders 6, 7, 8, and 9 are brought into position to print and may print during the next quarter of a revolution of said spur-gears 15 or during any part of said movement, and upon completion of said quarter-turn the web is again shifted and continues its movement until the next succeeding quarter-turn of said spur-gears 15 is completed, as will be obvious. The cylinder 6 may print 15 in one color and the cylinder 7 in a different color over a part of the surface, or one of said cylinders may number the sheets printed by the other cylinder, and this operation would be repeated by the cylinders 8 and 9 on 20 the other side of the web. In order to cause the impressions made by the cylinders 8 and 9 to register with those made by the cylinders 6 and 7, the compensators 36 are set in a well-known manner, so that the web will be so fed 25 upon the printing-bed 3 as to bring the printed surfaces directly over the impression portion of said bed 3. In the position of the crank-pin as shown in Fig. 1 the full stroke is imparted to the rack, and the web is consequently shifted to the fullest extent—that is, 30 a distance equal to the entire length of the impression-surface of each of the printing-beds and double the length of the surface printed by any one of the cylinders 6, 7, 8, and 9, so 35 that when said web is shifted such distance the cylinder 6 will print on one part of the surface and the cylinder 7 on another part, while cylinder 8 will print over the same surface printed by the cylinder 6 either on the 40 same or opposite side of the web, depending upon the manner of passing said web. By reducing the throw of the rack one-half all of the printing-cylinders will print consecutively over the same surface. After being thus 45 printed the web is passed over the roller 38 and thence over the compensator 39, which is adjusted to feed the web to the cutting devices 41 in such a manner as to cause the same to be cut off between the printed portion of 50 the surfaces. The said cutter 41 is operated from an eccentric 66 on the drive-shaft, which is connected with a rock-shaft 67 and the latter being in turn connected with the said cutter, said devices being old and well known and 55 forming no part of my invention.

Other devices shown in the drawings, such as the means for adjusting the position of the journals 10 relatively to the frame 12 in order to bring the printing-cylinders in proper 60 position relatively to the printing-beds and the gearing for rotating the inking-rollers, &c., are all well known and do not require special description and illustration, and I have therefore omitted some of these devices and 65 have indicated others only in dotted lines.

It will be obvious that in shifting the web 30 it is very essential to proper register that there should be no lost motion in the shifting devices and as with the use of ratchet-wheels there is necessarily some lost motion I prefer 70 to use the friction-clutch devices shown in Fig. 5, in which 35 is the member rigid with the shaft of the roller and 43 the gear carrying a plurality of spring-actuated friction-dogs 44, normally held in contact with the surface of the member 35 and passing loosely over same when said gear 43 is revolved in one direction, but when revolved in the opposite direction clutching said member 35 and causing same to be revolved in unison with the 80 gear 43 without lost motion.

My said press is adapted for a large variety of purposes and is capable of many slight modifications to adapt it to certain purposes.

If the web 30 is to be printed on one side 85 only, then it is led, as shown in Fig. 9, over the bed 2 in the opposite direction and from the upper end of the latter over the upper end of the bed 3, thus presenting only one face to be printed upon. In this manner said face 90 may be printed in four colors in one passage through the press, or it may be printed in three colors and the cylinder 9 be provided with scoring-knives and cutters 68, by means of which the web is scored and cut for producing paper boxes.

My construction is particularly advantageous, inasmuch as the printing-beds are concentric with the pivot on which the oscillating frame 12 swings, thereby rendering adjustment very easy and obviating the numerous parts subjected to wear with which printing-presses are usually encumbered and which are a constant source of trouble.

My said press is designed mainly for the 105 cheaper classes of work, particularly where a plurality of colors are desired without the usual increase in cost resulting from the necessity of passing the sheets a number of times through the press. I do not wish it to be understood, however, that my said press is incapable of producing high-class work.

I claim as my invention—

1. In a printing-press, the combination with a segmental impression-bed, and devices for feeding a web to be printed intermittently over same, of an oscillating frame swinging in an arc concentric with said impression-bed and carrying the printing devices movable over said bed.

2. In a printing-press, the combination with a segmental impression-bed, and an oscillating frame swinging in an arc concentric with said bed and carrying the other member of the printing-couple, of web-feeding devices coacting with said last-named member of said printing-couple, to feed the web to be printed at intervals over said bed.

3. In a printing-press, the combination with a segmental impression-bed, and an oscillating 130

frame swinging in an arc concentric with said bed and carrying the other member of the printing-couple, of web-feeding devices coacting with said last-named member of said printing-couple to feed the web to be printed a predetermined distance between the printing intervals.

4. In a printing-press, the combination with an oscillating member carrying the printing member, and an impression-bed concentric with said oscillating member, of web-feeding devices coacting with said oscillating member and engaging the web to be printed for moving said web a predetermined distance between the printing operations.

5. In a printing-press, the combination with an oscillating member carrying the printing member, and an impression-bed concentric with said oscillating member, of web-feeding devices coacting with said oscillating member and engaging the web to be printed for moving said web a predetermined distance as said oscillating member is adjacent either limit of its movement.

6. The combination with an oscillating member, a printing-cylinder carried thereby, an impression-bed concentric with said oscillating member and over which said cylinder moves, and a raised printing-plate on said printing-cylinder, of web-shifting devices coacting with said oscillating member to shift said web when said raised portion of said cylinder is out of printing relation with said bed.

7. The combination with an oscillating member, a printing-cylinder carried thereby, an ink-distributing surface on said cylinder, a raised printing-plate carried by said cylinder, and an impression-bed concentric with the axis of said oscillating member, of intermittently-actuated web-shifting devices and means for imparting motion thereto when said raised printing-plate carried by said cylinder is out of printing relation with said bed.

8. In a printing-press, the combination with a segmental impression-bed, concentric racks at each side of said bed, and an oscillating frame swinging in an arc concentric with said bed, of a printing-cylinder carried by said oscillating frame and movable over said bed, spur-gears rigid with said cylinder and meshing with said racks, a raised printing-surface partially covering said cylinder, web-shifting devices, and gearing controlling the movements of said oscillating frame and said web-shifting devices to actuate the latter when said printing-surface of said cylinder is out of printing relation with said bed and the web is free.

9. In a printing-press, the combination with a rigid segmental impression-bed, racks at each side thereof, concentric therewith, an oscillating frame swinging in an arc concentric with said bed, a printing-cylinder carried by said frame, spur-gears rigid with said cylinder and meshing with said rack, and a

raised printing-surface covering part of said cylinder, of web-shifting devices, gearing between said web-shifting devices and said oscillating frame for operating said shifting devices when said printing-surface of said cylinder is out of printing relation with said bed, and means for regulating the movements of said web-shifting devices for varying the feed of the web.

10. In a printing-press, the combination with a rigid impression-bed, an oscillating frame, a printing-cylinder carried by said frame and movable over said bed, and a raised printing-surface covering part of said cylinder, of web-feeding devices and gearing between said web-feeding devices and said frame for feeding said web when said printing-surface of said cylinder is out of printing relation with said bed.

11. In a printing-press, the combination with a rigid impression-bed, an oscillating frame, a printing-cylinder carried by said frame and movable over said bed, and a printing-surface covering part of said cylinder, of web-feeding devices, means common to said frame and said web-feeding devices for operating the latter when said printing-surface of said cylinder is out of printing relation with said bed, and means for varying the feed of said web to accord with the length of the impression made by said cylinder.

12. In a printing-press, the combination with a rigid impression-bed, an oscillating frame, a printing-cylinder carried by said frame and movable over said bed, and a raised printing-surface covering part of said cylinder, of web-feeding devices, a reciprocating rack controlling same, means for varying the stroke of said rack to vary the length of web fed, and means common to said rack and said oscillating frame for actuating said web-feeding devices when said printing portion of said cylinder is out of printing relation with said bed.

13. In a printing-press, the combination with a rigid impression-bed, an oscillating frame, a printing-cylinder carried by said frame and movable over said bed, and a raised printing-surface covering part of said cylinder, of web-feeding devices, a reciprocating rack controlling same, an adjustable crank operating said rack and adapted to vary the stroke thereof to vary the feed of said web, and gearing between said crank and said oscillating frame to operate said web-feeding devices when the printing-surface of said cylinder is out of printing relation with said bed.

14. In a printing-press, the combination with an impression-bed, a rack rigid therewith, a printing-cylinder, spur-gears carried thereby and meshing with said rack, a raised printing-surface partially covering said cylinder, and means for setting said members in relative motion for printing, of web-shifting devices, a reciprocating member, clutch devices operable from said reciprocating member and

adapted to clutch and actuate said web-shifting devices when said reciprocating member moves in one direction, and gearing between said means for operating said printing members and said reciprocating member for actuating said web-shifting devices when said printing members are out of printing relation.

15. In a printing-press, the combination with an impression-bed, a rack rigid therewith, a printing-cylinder, spur-gears carried thereby and meshing with said rack, a raised printing-surface partially covering said cylinder, and means for setting said members in relative motion for printing, of web-shifting devices, a reciprocating member, clutch devices operable from said reciprocating member and adapted to clutch and actuate said web-shifting devices when said reciprocating member moves in one direction, means for varying the stroke of said reciprocating member for regulating the length of web fed, and gearing between said printing members and said reciprocating members for causing said web-shifting devices to be actuated when said printing members are out of printing relation with each other.

16. In a printing-press, the combination with an impression-bed, a plurality of printing-cylinders movable over different parts of said impression-bed and provided with segmental raised printing-surfaces covering part of the surface of each cylinder, and means for simultaneously operating said cylinders, of web-shifting devices, gearing between the same and said cylinder-operating devices to actuate said web-shifting devices between the printing intervals, and means for varying the feed of said web to present a fresh surface simultaneously to all cylinders or to present the same surface successively to each of same.

17. In a printing-press, the combination with an impression-bed, a plurality of cylinders simultaneously movable over different parts of said bed and provided with raised printing-surfaces covering part of the periphery of each cylinder, and means imparting motion to said cylinder, of web-shifting devices, gearing between the same and said cylinder-operating devices to actuate said web-shifting devices when said printing portions of said cylinders are out of printing relation, and means for regulating the length of web fed at each operation including a reciprocating member having a variable throw, gearing between said member and said web-shifting devices, and means for throwing said gearing into operation when said member moves in one direction.

18. In a printing-press, the combination with an impression-bed, a plurality of printing members each operating on a different portion of said bed, and means for simultaneously operating said printing members, of web-feeding mechanism, gearing between the same and said printing members for actuating said web-

feeding devices between the printing intervals, and means controlling the length of web fed at each operation, including a reciprocating member, a crank, and a radially-adjustable crank-pin engaging said reciprocating member to vary the stroke thereof.

19. In a printing-press, the combination with two oppositely-disposed impression-beds, printing members movable over said beds, and a single frame common to both said members, of web-shifting devices, gearing common to the latter and said frame to actuate said web-shifting devices between the printing intervals, compensating devices between said impression-beds engaging said web, and means for varying the feed of said web.

20. In a printing-press, the combination with two oppositely-disposed impression-beds, printing members movable over each of said beds, and connection between said members for simultaneously operating same, of web-shifting devices, and gearing between the latter and said printing members for actuating said web-shifting devices between the printing intervals.

21. In a printing-press, the combination with the oppositely-disposed impression-beds, printing members movable over each of said beds, and connection between said members for simultaneously operating same, of web-shifting devices, and gearing between the latter and said printing members for actuating said web-shifting devices between the printing intervals, and devices controlling said web-shifting devices for varying the stroke thereof, including a radially-adjustable crank-pin engaging a part of said web-shifting mechanism.

22. In a printing-press, the combination with a plurality of impression-beds, a plurality of printing members movable over each of same, means for simultaneously operating all of said printing members, and web-shifting devices common to both said beds, of gearing common to said printing members and said web-shifting devices for actuating the latter between the printing intervals.

23. In a printing-press, the combination with a plurality of impression-beds, a plurality of printing members movable over each of same, means for simultaneously operating all of said printing members, and web-shifting devices common to both said beds, of gearing common to said printing members and said web-shifting devices for actuating the latter between the printing intervals, and means for varying the throw of said web-shifting devices including a radially-adjustable revolute crank-pin engaging a part of said web-shifting mechanism.

24. In a printing-press, the combination with a plurality of impression-beds, a plurality of printing members movable over each of same, means for simultaneously operating all of said printing members, and web-shifting devices

common to both said beds, of gearing common to said printing members and said web-shifting devices for actuating the latter between the printing intervals, compensating devices between the impression-beds engaging the web to control the register, and means for varying the throw of said web-shifting devices including a radially-adjustable revolute crank-pin engaging a part of said web-shifting mechanism.

25. In a printing-press, the combination with a plurality of impression-beds, a web movable consecutively over said beds, printing members movable simultaneously over said beds and printing consecutively over each given section of said web, and compensating devices engaging said web to control the register thereof of said various beds, of web-shifting devices, gearing common to said printing members and said web-shifting devices to actuate the latter between the printing intervals, and means controlling said web-shifting devices to vary the throw thereof.

26. In a printing-press, the combination with a plurality of impression-beds, a web movable consecutively over said beds, printing members movable simultaneously over said beds and printing consecutively over each given section of said web, and compensating devices engaging said web to control the register thereof on said various beds, of web-shifting devices, gearing common to said printing members and said web-shifting devices to actuate the latter between the printing intervals, and means controlling said web-shifting devices to vary the throw thereof, including a radially-adjustable revolute crank-pin engaging a part of the web-shifting mechanism.

27. In a printing-press, the combination with two diametrically opposite segmental impression-beds, printing members movable over same, and an oscillating frame swinging on the axis of said impression-beds, of web-shifting mechanism, gearing common to the latter and said oscillating frame to actuate said web-shifting mechanism between the printing intervals, means for varying the feed of the web to accord with the length of the impression thereon at each operation, and compensating

devices between said impression-beds engaging said web to control the register.

28. In a printing-press, the combination with the diametrically opposite concentric segmental impression-beds, an oscillating frame swinging on the axis of said impression-beds, two cylinders at each end of said frame moving over said impression-beds, and having raised printing-surfaces, a web movable consecutively over said beds, and compensating devices between said beds engaging said web and controlling the register on the second bed, of web-shifting mechanism, gearing common to said oscillating frame and web-shifting mechanism to operate the latter between the printing intervals, devices interposed in said gearing for varying the throw of said web-shifting mechanism, a revolute roll from which the web is taken, and variable-speed gearing engaging said roll to revolve the same at a uniform speed in accordance with the rapidity of operation of said web-shifting mechanism.

29. In a printing-press, the combination with a bed, and a frame movable over said bed, of a cylinder journaled in bearings in said frame and having its surface divided into two segmental parts of different radius, one of said parts forming an ink-distributing surface and the other thereof a printing-surface, and ink-distributing rollers journaled in said frame and adapted to be brought alternately in contact with said two parts of the surface of said cylinder as the latter revolves.

30. In a printing-press, the combination with a bed and a revolute cylinder, said bed and cylinder being relatively movable, of members carrying said cylinder, inking-rollers journaled in said member and held in contact with said cylinder, an ink-distributing surface on said cylinder and a printing-surface on said cylinder of longer radius than said inking-surface adapted to receive ink from said rollers.

In testimony whereof I affix my signature in presence of two witnesses.

JAMES ROWE.
